FREDERICK A. HART, OF NEWARK, NEW JERSEY, ASSIGNOR, BY MESNE ASSIGNMENTS,
TO UNDERWOOD COMPUTING MACHINE COMPANY, OF NEW YORK, N. Y., A CORPO-
RATION OF NEW YORK.

TYPE-WRITING MACHINE.

1,213,189.

Specification of Letters Patent.

Patented Jan. 23, 1917.

Application filed March 30, 1915. Serial No. 17,998.

To all whom it may concern:

Be it known that I, FREDERICK A. HART, a citizen of the United States, residing in Newark, in the county of Essex and State of New Jersey, have invented certain new and useful Improvements in Type-Writing Machines, of which the following is a specification.

This invention relates to means for squaring the leading edges of work-sheets with relation to the printing line on the platen of a typewriting machine, and to means for feeding the work-sheets.

A feature of the invention is to provide improved means at the delivery side of the platen for squaring the work-sheets thereon, together with means for feeding the sheets accurately after they have passed beyond the control of the usual platen feed rolls, thereby enabling the printing to be extended to the bottom edge of the work-sheet.

A paper squaring table for the work-sheets may be located at the delivery side of the platen and extend upwardly and rearwardly from the platen to form a support for the work-sheets as they are adjusted to a squaring gage at the upper edge of the table. A work-sheet-feeding couple may comprise feed rolls above and beneath the squaring table, the lower feed rolls projecting through openings in the table to bring the bite of the rolls substantially in the plane of the upper surface of the table for holding and feeding the work-sheets while the latter are supported on the table. The table, or a portion thereof, may extend between the platen and the work-feeding couple in position to guide the leading edge of the work to the bite of the rolls when the work is advanced by the rotation of the platen. The said feed rolls may be separated to permit placing and adjustment of the work-sheets on the table or their removal from the machine, and the paper squaring gage at the upper end of the table enables the operator to square the leading edges of the sheets with respect to the printing line on the platen.

In the McCormack Patent 929,158, is disclosed a gage for the leading edges of the sheets, said gage being mounted above the platen at the top of an upstanding plate upon which the leading edges of the sheets are adjusted, and said gage is movable out of the path of the sheets. It is found in forming a certain class of work that suffi-

cient accuracy of register is not maintained among the several sheets when they are drawn around the platen, even though they are initially in register at their upper edges. The register of each sheet with all the others 60 is impaired, because the wrapping of a number of sheets around the platen has the effect of enlarging the diameter of the platen, whereby the outer sheet travels at a different speed from the inner sheet as the platen revolves; all the sheets being, in said McCormack patent, pressed against the platen to revolve therewith. Where many copies have to be made simultaneously, and where each sheet is provided with horizontal rulings 70 with which it is intended that the type impressions shall register, it is found that perfect register of the type impressions with the ruled lines is not secured, owing to the aforesaid difference in speed of travel of the 75 outer sheets relatively to the inner sheets, whereby the ruled lines upon the outer sheets appear to creep in respect to those upon the inner sheets. Thus when a number of sheets are fed together around the platen there is a 80 tendency for the leading end of the outer sheet or sheets to creep relatively to the leading ends of the inner sheets, owing to the greater arc through which they must travel, on account of their greater distance from the 85 axis of the platen. As a result, the leading edges of the sheets, if gaged before being advanced around the platen, are, when the sheets are brought to printing position, separated or stepped, with the innermost 90 sheets a substantial distance out of register with the outer sheets. With the sheets thus out of register, the types will not print at the same relative position on the several sheets. If the sheets are ruled and the outer 95 sheet is brought with a ruled line to the printing line of the platen so that the printing line extends along the ruled line, the duplicated printing on the underlying sheets will be out of register with the rulings of 100 said underlying sheets. In the present invention this difficulty is overcome, because when the several sheets are adjusted to the gage, the rulings thereof are in accurate register, and this is maintained. The co-oper- 105 ating feed rolls in advance of the printing line serve to retain the sheets in register and feed them past the printing line at the same speed. These advance feed rolls are geared to the platen, so that the pack of sheets may 110

be fed between them at the same surface speed as that of the platen; and when the advance feed rolls are used for the purpose of feeding a pack of horizontally-ruled sheets which must be kept in accurate register, the usual bottom feed rolls may be cast off, so as not to force the sheets against the platen, which would interfere with the uniform feeding of all the sheets which is effected by said advance rolls. When the machine is used for other purposes, the bottom feed rolls may press the sheet or sheets against the platen, and the advance rolls may be either working or released, as circumstances may require. Thus the machine is capable of a wide range of use with substantial advantage.

The squaring gage is automatically withdrawn from the path of a work-sheet when the feed rolls are returned to position to clamp the sheet. The separation of said feed rolls may be effected by mounting the upper rolls of the couple to rotate on a shaft having eccentric bearings in the ends of the platen frame, said shaft rotatable by a hand crank to separate the rolls or return them to operative position.

The feed rolls may be positively driven from the platen by a gear train comprising a gear on the platen and intermeshing gears on the shafts of the feeding couple, whereby both members of the couple are positively driven. The provision for positively driving both members of the couple is of value in securing a reliable and positive feeding of the work-pieces, and is of special importance when the platen is of great length. The said feeding couple may cooperate with the usual platen feed rolls running on the under surface of the platen, to feed the work-sheets over the platen, and also positively operates to feed the work-sheets and hold them in alinement on the platen after the lower edges of the work-sheets have passed beyond the platen feed rolls. The work-sheets may thus be fed forward, and the printing continued to the bottom of the sheets, or as close to the bottom as desired.

Other features and advantages will hereinafter appear.

In the accompanying drawings, Figure 1 is a perspective view of the invention applied to an Underwood typewriting machine. Fig. 2 is a sectional end elevation view. Fig. 3 is an end elevation with the paper gage in operative position, and the rolls of the feeding couple separated. Fig. 4 is a similar view with the gage thrown to its inoperative position, and the feed rolls in operative position.

The platen 5 is mounted on an axle 6 journaled in the ends of a platen frame 7, the latter mounted on a carriage 8. Types 9 are operated in the usual manner, to strike upwardly and rearwardly against the front

face of the platen to print on work-sheets 10. The platen may be rotated for line-spacing by means of the line-space lever 11, which operates a slide 12 carrying a pawl to drive the line-space ratchet wheel 13 secured to the platen axle. The platen may also be rotated by the usual hand wheels 14 on the platen axle. Front and rear feed rolls 15 and 16 run on the under surface of the platen and co-operate with the latter to feed work-sheets around the under surface of the platen and upwardly past the printing line. These feed rolls may be thrown off the platen by a key 17 connected through a link 18 to a rock shaft 19 formed with flats or cams 20 to rotate levers 21 carrying the feed rolls, so that when the key 17 is depressed, the rolls are thrown off the platen.

The parts thus far described may be of the usual construction found in the commercial Underwood machine.

A paper adjusting and squaring table or plate 22, which may be mounted on the platen frame, extends upwardly and rearwardly from the front face of the platen. A paper squaring gage 23 carried on brackets 24, may be swung forwardly (by means hereinafter described) from the Fig. 2 position to the Fig. 3 position, in which it projects forward past the surface of the table and parallel with the printing line to enable the operator, by bringing the leading edges of the work-sheets against the gage, to square the sheets with relation to the printing line on the platen. The gage 23 is operated in conjunction with a work-sheet-feeding couple, comprising rolls 25 over the table 22, and rolls 26 beneath the table, and projecting through openings in the table, the line of contact of the rolls 25 and 26 being substantially in the plane of the table surface so that the rolls grip the work-sheet while the latter lies flat on the table.

The upper and lower rolls 25 and 26 are respectively mounted on hollow shafts 27 and 28, said hollow shafts being loosely mounted on shafts 29 and 30, the latter supported in brackets 31 and 32 on the platen frame. The mounting for the shaft 29 comprises an eccentric 33 fixed to said shaft and journaled in the bracket 31, and a sleeve 34 fixed to the shaft eccentric thereto and journaled in the bracket 32. A crank 35 is fixed to the shaft 29 and provided with a handle 36 to rotate the shaft, and thereby move the feed rolls 25 into and out of engagement with the rolls 26. A spring 37 connected to the crank 35 holds the latter in either position, and a stop 37^a on the sleeve 34 limits the throw of the crank in the direction to separate the rolls. The crank 35 also serves to throw the gage 23 into and out of operative position, and for this purpose the brackets 24 which carry the gage are fixed to rock arms 39 on a rock shaft 40. A link 130

38 connects the shaft 29 with one of the rock arms 39, whereby the movement of the shaft 29, as the feed rolls 25 and 26 are separated, rocks the shaft 40 and swings the gage 23 to the Fig. 3 position. When the feed rolls 25 are returned to operative position, the gage 23 is thrown down to the Fig. 2 position, so as not to obstruct the passage of the work-sheets. The brackets 24 might be mounted directly on the shaft 40, but the arrangement shown is preferable for purposes of construction and assembling.

The feed rolls 25 and 26 are positively driven by a gear train comprising a gear wheel 41 fixed to the platen axle, an idler gear 42, a gear pinion 43 secured to the shaft 28 and a gear pinion 44 secured to the shaft 27. The feed rolls 25 and 26 are thus positively driven when the platen is rotated in either direction.

The pitch circle of the gear 41 has preferably the same diameter as the platen, and the diameters of the pitch circles of the gears 43 and 44 are likewise preferably equal to the diameters of the feed rolls 26 and 25, to cause the feed rolls to be driven at the same surface speed as the platen, although this result might be effected by other arrangements of gears. The positive driving of the rolls 25 by means of the gear train is of value in insuring a positive feed of the work-sheets, particularly where the platen is of great length.

One or more work-piece-holding fingers 35 50 (Fig. 2), each carrying a roll 51 to bear against the work-pieces on the platen, may be pivotally mounted on the carriage 8 to swing horizontally to inoperative position.

To permit the work to be positioned on the platen, the platen feed rolls 15, 16 are thrown off the platen by depressing the key 17, and the crank 35 is swung to the left to separate the feed rolls 25, 26. The work may then be quickly positioned, with the leading end thereof resting on the table 22 while the forward edges of the sheets are moved up against the gage 23, thereby squaring the sheets with relation to the printing line.

50 When it is desired to use the machine for writing many sheets simultaneously, if said sheets have no horizontal rulings on them, or if, for any other reason, it is unnecessary to keep them accurately in register throughout the writing of the page, either the bottom rolls 15, 16, or the advance rolls 25, 26, may be employed for feeding the sheets; and if the bottom rolls 15, 16, are employed, and the advance rolls 25, 26, are at the same time released, it is obvious that when or before the bottom edges of the sheets pass the front bottom roll 15, the advance rolls 25, 26, may be brought into use to feed the pack of sheets upwardly beyond said roll 15. But if the sheets in the pack

are horizontally ruled, or if, for any other reason, it is desired that they shall be fed in accurate horizontal register throughout the writing of the page, the rolls 15, 16, may be cast off by the usual release key 17, so that they cannot mis-feed the sheets around the platen by holding the sheets thereagainst; and the advance rolls 25, 26, are alone depended upon for feeding the pack of sheets around the platen, throughout the writing of the page. These advance rolls 25, 26, are so placed with relation to the printing line that the sheets stand in substantially straight position from the printing line to and beyond the rolls, the straight sheets being about tangential to the platen and both rolls, that is, the sheets are not curved around the platen to any appreciable extent between the printing line and the rolls, nor are they curved around the introductory side of either roll, and hence it follows that after the sheets are once gaged together against the leading edge gage 23 and caught in the grip of said rolls 25, 26, they must advance each to the same extent 90 throughout the writing of the page, and hence, at the printing line, each must register with all the others throughout said writing of the page, even if, below the printing line, they happen to be out of register 95 where they curve around the underside of the platen. Being therefore in register at the printing line throughout the entire writing of the page, the result is secured that all the carbon impressions, as well as the ink- 100 ribbon impressions, fall accurately upon the horizontal rulings upon all the sheets. The advance rolls 25, 26, being geared to the platen, are controlled by the line-feeding mechanism, and hence line-feed the paper with the desired accuracy. While the sheets are held in adjusted position between the separated rolls the crank 35 may be returned to cause the rolls 25, 26 to grip the sheets, the gage 23 being simultaneously 105 withdrawn out of the path of said sheets. The platen feed rolls 15, 16 are also restored by lifting the key 17. The work-sheet or sheets may now be fed backward to bring the printing line as near as desired to the leading edge thereof. If the work is withdrawn from the feed rolls 25, 26 during this backward movement, the platen feed rolls 15, 16 hold it against displacement, and as it is advanced during the writing operation, 110 it is guided over the table 22 and again gripped by the feed rolls 25, 26. As the bottom of the sheet approaches the printing line, it may pass beyond the control of the platen feed roll 15, but the rolls 25, 26 are 115 still operative to feed it and enable the writing to be continued to the bottom of the page or as near the bottom edge as desired. The rolls 51 in addition to serving their usual function of card or work-piece hold- 120

125

130

ers, may also assist the rolls 25, 26 in holding sheets closely against the platen after they have passed the roll 15.

5 Variations may be resorted to within the scope of the invention, and portions of the improvements may be used without others.

Having thus described my invention, I claim:

10 1. The combination with a rotary platen and means coöperating therewith to feed a work-sheet over the platen, of a work-sheet-feeding couple comprising feed rolls at the delivery side of the platen to engage the work-sheet at a point in advance of the printing line, a squaring gage located in advance of said couple and against which the leading edge of the work-sheet may be set to square the sheet with reference to the printing line on the platen, a paper- 15 supporting and squaring table on which the forward end of the sheet is supported while being adjusted to said gage, means to separate said feed rolls to permit said adjustment of the work-sheet, and means to automatically withdraw the squaring gage from the path of the work-sheet when said rolls are brought into gripping engagement with the work-sheet.

30 2. The combination with a rotary platen and work-sheet-feeding means coöperating therewith to advance work-sheets over the platen past the printing line, the printing line being in advance of said feeding means, of a pair of feed rolls at the delivery side 35 of the platen, means to separate said rolls to permit the adjustment of the work-sheets therebetween, a gage located beyond said rolls in position to be engaged by the leading edges of the work-sheets, and means to 40 drive said rolls from the platen at the surface speed of the platen and thereby assist in advancing the work-sheets, said rolls operable to positively feed a work-sheet and maintain it in alinement on the platen when the bottom edge of the work-sheet has 45 passed beyond the said first-mentioned feeding means, thereby enabling the printing to be continued and the alinement of the work-sheet on the platen maintained until the printing has reached the bottom of the work-sheet.

55 3. The combination with a rotary platen and work-sheet-feeding means coöperating therewith to advance work-sheets over the platen past the printing line, the printing line being in advance of said feeding means, of a pair of feed rolls at the delivery side 60 of the platen, means to drive said rolls from the platen at the surface speed of the platen and thereby assist in advancing the work-sheets, said rolls operable to positively feed a work-sheet and maintain it in alinement on the platen when the bottom edge of the work-sheet has passed beyond the said first- 65 mentioned feeding means, thereby enabling

the printing to be continued and the alinement of the work-sheet on the platen maintained until the printing has reached the bottom of the work-sheet, and a paper-table extending between said feed rolls and the platen and on which the work-sheets are supported and guided.

4. The combination with a rotary platen and work-sheet-feeding means coöperating therewith to advance work-sheets over the platen past the printing line, the printing line being in advance of said feeding means, of a pair of feed rolls at the delivery side 75 of the platen, means to drive said rolls from the platen at the surface speed of the platen and thereby assist in advancing the work-sheets, said rolls operable to positively feed a work-sheet and maintain it in alinement on the platen when the bottom edge of the work-sheet has passed beyond the said first- 80 mentioned feeding means, thereby enabling the printing to be continued and the alinement of the work-sheet on the platen maintained until the printing has reached the bottom of the work-sheet, a paper-table extending between said feed rolls and the platen and on which the work-sheets are supported and guided, 85 and a squaring gage for the leading edge of the work-sheet projecting past the surface of the table into the path of the sheet to enable the sheet to be squared with relation to the printing line while the sheet is supported on said table.

5. The combination with a rotary platen and work-sheet-feeding means coöperating 100 therewith to advance work-sheets over the platen past the printing line, the printing line being in advance of said feeding means, of a pair of feed rolls at the delivery side 105 of the platen, means to drive said rolls from the platen at the surface speed of the platen and thereby assist in advancing the work-sheets, said rolls operable to positively feed a work-sheet and maintain it in alinement on the platen when the bottom edge of the 110 work-sheet has passed beyond the said first-mentioned feeding means, thereby enabling the printing to be continued and the alinement of the work-sheet on the platen maintained until the printing has reached the 115 bottom of the work-sheet, a paper-table extending between said feed rolls and the platen and on which the work-sheets are supported and guided, a squaring gage for the leading edge of the work-sheet projecting 120 past the surface of the table into the path of the sheet to enable the sheet to be squared with relation to the printing line while the sheet is supported on said table, said feed rolls being located between the 125 squaring gage and the printing line on the platen, the line of contact between said rolls being substantially in the plane of the surface of said table, means for separating said rolls to permit adjustment of the sheet, and 130

a connection between said last-named means and the gage for automatically throwing the gage out of the path of the work-sheet when the rolls are brought together to feed the 5 work-sheet.

6. In a typewriting machine, the combination with a rotary platen, of a pair of feed rolls at the delivery side of the platen and separated therefrom, and work-sheet-feeding 10 rolls running on the platen at the opposite side of the printing line from said pair of feed rolls and coöperating with the platen to feed the work-sheets past the printing line, said pair of rolls operable to hold the 15 work-sheets squared to the platen and feed them over the platen at the surface speed of the platen as the sheet is advanced beyond the feed rolls on the platen, and so mounted with relation to each other and to 20 the platen that the sheets may extend in substantially straight condition from the printing line on the platen past the bite of the rolls, tangentially to both the platen and each roll.

25 7. In a typewriting machine, the combination with a rotary platen, of a pair of feed rolls at the delivery side of the platen, work-sheet feeding means at the opposite side of the printing line from said feed rolls 30 and coöperating with the platen to feed work-sheets past the printing line, said feed rolls operable to hold a work-sheet in alignment on the platen and to feed the work-sheet over the platen after the bottom edge 35 of the sheet has passed beyond said feeding means, a squaring gage for the leading edge of the work-sheet located beyond said pair of rolls, and means for separating said rolls to permit a sheet to be squared by said gage 40 while positioned between said rolls.

8. The combination with a rotary platen, of a feeding couple located at the delivery side of the platen, means to direct the leading end of a work-sheet to said couple as it 45 is advanced beyond the printing line, and a gear train comprising a gear on the couple and a gear connected to rotate with the platen, the gear train forming a means for positively driving said feeding couple at 50 the surface speed of the platen when the platen is driven.

9. In a typewriting machine, the combination with a rotary platen, of means at the delivery side of the platen and separate 55 therefrom for line-feeding a work-sheet, said means comprising a feed roll to run on the outer face of the work-sheet, means to direct the leading edge of the work-sheet to said feed roll as it is advanced beyond the platen, 60 and means for positively driving said roll from the platen at the surface speed of the platen.

10. The combination with a rotary platen, of a pair of feed rolls at the delivery side 65 of the platen for line-feeding a work-sheet

thereover, means for positively driving said rolls from the platen at the surface speed of the platen, and a table extending between the platen and the feed rolls in position to support the leading end of the work-sheet 70 as it is advanced beyond the printing line and direct it to the bite of said rolls.

11. In a front-strike writing machine, the combination with a rotatable platen having its printing line along the front face thereof, of platen feed rolls running on the under surface of the platen, a work-sheet-supporting table extending upwardly and rearwardly from the platen in advance of the printing line, and a pair of feed rolls 75 having their line of contact substantially in alignment with the surface of said table, a portion of said table extending between the platen and said rolls and forming a means to support and guide the leading end of a 80 work-sheet from the platen to said rolls, and said rolls forming means for positively feeding the work-sheet and holding it in alignment on the platen after the bottom edge of the work-sheet has passed beyond 85 the said platen feed rolls.

12. In a front-strike writing machine, the combination with a rotatable platen having its printing line along the front face thereof, of platen feed rolls running on the under surface of the platen, a work-sheet-supporting table extending upwardly and rearwardly from the platen in advance of the printing line, a pair of feed rolls having their line of contact substantially in 90 alignment with the surface of said table, 95 said table forming a means to support and guide the leading end of a work-sheet from the platen to said rolls, and said rolls forming means for positively feeding the work-sheet and holding it in alignment on the platen after the bottom edge of the work-sheet has passed beyond 100 the said platen feed rolls, a squaring gage projecting forward beyond the surface of said table into the 105 path of the work-sheet, means for separating said feed rolls to permit the work-sheet to be placed therebetween and squared by said gage, and means controlled by said feed roll-separating means for withdrawing the 110 gage from the path of the work-sheet when the rolls are brought together, and restoring the gage to operative position when the rolls are separated.

13. In a front-strike typewriting machine, 120 the combination of a roller platen, a work-sheet supporting table extending upwardly and rearwardly from the platen at the delivery side thereof, a work-sheet feeding roll overlying said table and parallel with 125 the platen to engage the surface of the work-sheet intermediate the upper and lower edges of said table, and means co-operating with said roll for feeding a work-sheet over the table.

14. In a front-strike typewriting machine, the combination of a roller platen, a work-sheet supporting table extending upwardly and rearwardly from the platen at the delivery side thereof, a work-sheet feeding roll overlying said table and parallel with the platen to engage the surface of the work-sheet intermediate the upper and lower edges of said table, means coöperating with said roll for feeding a work-sheet over the table, a gage at the upper edge of said table for the leading edge of the work-sheet to enable said sheet to be squared with reference to the printing line, and means for lifting said feeding roll from the table to permit the work-sheet to be adjusted and its edge set to said gage.

15. In a front-strike typewriting machine, the combination with a rotatable platen, of a work-sheet supporting table extending upwardly and rearwardly from the platen at the delivery side thereof, a work-sheet feeding couple comprising one member overlying said table parallel with the platen in position to engage the upper surface of a work-sheet on said table along a line intermediate the upper and lower edges of said table, the table being provided with an opening or openings beneath said member, the other member of the couple being located beneath the table and projecting through said opening or openings to coöperate with the first-mentioned member of the couple to grip the work-sheet and feed it over the table, and means for driving said couple from the platen at the surface speed of the platen.

16. In a front-strike typewriting machine, the combination with a rotatable platen, of a work-sheet supporting and guiding table extending upwardly and rearwardly from the platen at the delivery side thereof, a feed roll overlying the table and extending parallel with the platen in position to engage the upper surface of a work-sheet on said table, the table being provided with an opening beneath said roll, a second feed roll beneath the table and projecting through said opening to coöperate with the first-mentioned roll to grip the work-sheet, line-space mechanism to rotate the platen, and means operated by the line-space mechanism to rotate said feed rolls at the surface speed of the platen when the line-space mechanism is operated.

17. In a front-strike typewriting machine, the combination with a rotary platen, of a work-sheet supporting table extending upwardly and rearwardly from the platen at the delivery side thereof, a work-sheet feeding couple comprising rolls located above and beneath said table respectively, the table provided with openings along the line of contact between said rolls to permit the rolls to grip the work-sheet, a shaft on which the upper rolls are mounted, eccentric bearings

for said shaft in the platen frame, means to rotate said shaft in its bearings to throw said upper rolls off the lower rolls, a gage in advance of said rolls to which the leading edge of the work-sheet may be adjusted to square the sheet on the platen, and means for withdrawing said gage from the path of the work-sheet when the upper rolls are moved to operative position and for projecting said gage into operative position when the rolls are separated.

18. The combination with a rotary platen and line-spacing means therefor, of means separated from the platen for advancing sheets around the same during the rotation thereof, said feeding means comprising a pair of coöperating rolls extending along the platen for gripping and advancing the sheet, said rolls capable of separation, to permit adjustment of a sheet or sheets therebetween, a gage positioned in advance of the printing line against which the sheets may be squared while between the separated rolls, and gearing between said line-spacing means and said feeding rolls.

19. The combination with a rotary platen, of means separated from the platen for advancing sheets around the same during the rotation thereof, said feeding means comprising a pair of coöperating rolls extending along the platen and capable of separation, a gage positioned to gage a sheet while the latter is between the separated rolls, a driving shaft upon which one of said rolls is mounted, and gearing between said driving shaft and the platen, inclusive of a pinion on said shaft, and also inclusive of a gear on the platen.

20. The combination with a rotary platen and line-spacing means therefor, of means separated from the platen for advancing a sheet around the same during the rotation thereof, said sheet-advancing means comprising a pair of coöperating rolls extending along the platen for gripping and advancing the sheet, toothed gearing between said line-spacing means and said feeding rolls, means to effect separation of said feeding rolls, a gage in position to square the sheets on the platen and bring their leading edges in register while the sheets are positioned between the separated feed rolls, and means to withdraw the gage when said feed rolls are brought together to grip the sheet.

21. In a typewriting machine, the combination with a rotary platen and line-spacing mechanism, of a pair of feed rolls at the delivery side of the platen, said feed rolls operable to hold a work-sheet in alinement on the platen, gearing between the line-spacing mechanism and the feed rolls for operating the latter to line-feed the work-sheet over the platen, a squaring gage for the leading edge of the work-sheet located beyond said pair of rolls, and means for sepa-

rating said rolls to permit a sheet to be squared by said gage while positioned between said rolls.

22. In a typewriting machine, the combination with a rotary platen, of a pair of feed rolls at the delivery side of the platen, said rolls operable to hold the work-sheets in register at the printing line on the platen and feed them past the printing line, the path of the sheets from the printing line to the rolls being about straight, a squaring gage for the leading edges of the work-sheets located beyond said rolls, said rolls separable to permit the work-sheets to be adjusted to the gage while positioned between said rolls, and means to hold said rolls separated during said adjustment of the sheets.

23. In a front-strike typewriting machine, the combination of a roller platen, a work-sheet-supporting table extending upwardly and rearwardly from the platen at the delivery side thereof, and a work-sheet-feeding roll parallel with the platen and overlying said table to engage the upper surface of the work-sheet intermediate the upper and lower edges of the table.

24. In a front-strike typewriting machine, the combination of a roller platen, a work-sheet-supporting table extending upwardly and rearwardly from the platen at the delivery side thereof, a work-sheet-folding roll parallel with the platen and overlying said table to engage the upper surface of the work-sheet intermediate the upper and lower edges of the table, and means to shift said roll away from the plane of the table to permit adjustment of the work-sheet between said roll and table.

25. In a front-strike typewriting machine, the combination of a roller platen, a work-sheet-supporting table extending upwardly and rearwardly from the platen at the delivery side thereof, a work-sheet-feeding roll parallel with the platen and overlying said table to engage the upper surface of the work-sheet intermediate the upper and lower edges of the table, means to rotate the platen, and means to drive said roll at the surface

speed of the platen when said platen-rotating means is operated.

26. In a front-strike typewriting machine, the combination with a rotary platen, of a work-sheet-feeding couple comprising rolls extending parallel with the platen and separated therefrom, a shaft on which one of the rolls is mounted, said shaft having eccentric bearings in the platen frame, means to rotate said shaft to separate said rolls, a gage in advance of said rolls to which the leading edge of the work-sheet may be adjusted to square the sheet on the platen, and means for withdrawing said gage from the path of the work-sheet when the rolls are brought to sheet-holding position and for projecting said gage into operative position when the rolls are separated.

27. In a typewriting machine, the combination of a platen, a work-sheet-feeding couple in advance of the printing line at the platen, a gage for the leading edges of the work-sheets, also in advance of the printing line, and means to operate said couple to feed sheets past the printing line, the path of the sheets between the printing line and said couple being about straight, whereby the sheets are retained in accurate register at the printing line.

28. In a typewriting machine, the combination of a platen, a work-sheet-feeding couple in advance of the printing line at the platen, a gage for the leading edges of the work-sheets, also in advance of the printing line, means to operate said couple to feed sheets past the printing line, the path of the sheets between the printing line and said couple being about straight, whereby the sheets are retained in accurate register at the printing line, feed rolls running on the platen, means to cast said feed rolls off the platen, and means to separate the members of said feeding couple independently of the means for casting off the platen feed rolls.

FREDERICK A. HART.
